UNITED STATES PATENT OFFICE.

EDWARD B. PARKHURST, OF WOBURN, MASSACHUSETTS, ASSIGNOR TO
JAMES T. FREEMAN AND HENRY F. DAVIS, OF SAME PLACE.

LEATHER-DRESSING MACHINE.

SPECIFICATION forming part of Letters Patent No. 604,903, dated May 31, 1898.

Application filed October 1, 1897. Serial No. 653,729. (No model.)

To all whom it may concern:

Be it known that I, EDWARD B. PARKHURST, a citizen of the United States, residing at Woburn, in the county of Middlesex and State 5 of Massachusetts, have invented certain new and useful Improvements in Jacks for Rolling, Glassing, &c., Leather, &c., of which the following is a specification, reference being had therein to the accompanying drawings.
10 I first shall describe my invention with reference to the accompanying drawings, which represent the best embodiment of the conception that I yet have contrived, and afterward I shall clearly point out and distinctly 15 define the essential characteristics of the invention in the claims at the close of this specification.

In the drawings, Figure 1 is a side elevation of a jack constructed in accordance with 20 my invention. Fig. 2 is a front elevation of the same.

The main frame of the machine consists of two parallel vertical webs 1 1, provided with suitable strengthening flanges and united by 25 the braces 2. Between the said webs are located most of the working parts of the jack. There is also an offset standard 3, united to one of the webs 1 by the braces 4. A shelf 5 for the reception of the stock is shown in Fig. 30 1 as affixed to the front of the machine, but is omitted from Fig. 2 for the sake of clearness.

6 7 are fast and loose pulleys on a shaft 8, which latter is journaled in the frame and 35 carries a fly-wheel 9.

10 is a pitman whose rear end is pivoted to the fly-wheel 9 and whose forward end bears a head 11, the latter being shown as provided with a pebbling-roll 12, although in 40 practice any other suitable tool or device may be applied to the said head, according to the character of the work for which the jack is to be employed.

To the head 11 is pivoted the lower end of 45 a beam 13, whose middle portion is connected to the frame by links 14 14 and whose upper end also is connected to the frame at the top thereof by the links 15 15.

16 is the bed, having, preferably, a surface 50 of wood, on which the leather is laid to be op-

erated upon, and 17 is the metal bed-frame upon which the said wooden surface is affixed.

The machine as thus far described is old and operates in the well-known manner. When the fly-wheel 9 is rotated, the pebbling- 55 roll or other tool or device carried by the head 11 traverses the table from front to rear in contact with the stock thereon, then lifts, then returns clear of the stock, and then descends and repeats its rearward traverse. 60

My invention relates particularly to the suspension and adjustment of the bed 16; and it consists in the mechanism designed to effect such suspension and adjustment with few and strong parts, having simplicity and compactness of construction, together with certainty and smoothness of operation. To this end I mount the bed, through the medium of connecting and supporting members, upon the free extremities of two levers that have 70 their inner or contiguous ends formed as toothed sectors, and thereby adapted to mesh or engage with each other. Thus in the drawings, 18 19 are two such contiguous levers, pivoted to the frame 1 at the points 20 21 and 75 having their contiguous ends adapted to engage with each other, preferably by being formed into sectors 22 23, that intermesh. The free ends 24 25 of the levers are connected by rods 26 27 to the table, thereby supporting the 80 latter. The rear rod 26 is non-adjustable, but is pivoted at each end, as shown. The two forward rods 27 27 are tapped through blocks 28 28, which latter are pivoted to the extremity 25 of the lever 19, (the said extremity being suitably formed with a lateral enlargement to support the said block,) and the 85 rods are provided with hand-wheels 29 29 for turning them up and down in the blocks 28 28 and for thereby adjusting the inclination 90 of the table for the purposes well known.

It will be apparent that in connection with the elements of my invention as thus far described I might employ a spring of any form and with any mode of connection and operation in order to sustain the table against the downward pressure of the pebbling-roll or other tool or device. Inasmuch as the simultaneous and equal elevation or depression of the engaging ends of the levers 18 19 is in- 100

sured by the action of the intermeshing sectors the free ends of the said levers must rise and fall together, and thereby must cause the elevation or depression of the table to occur in constant parallelism to itself. Consequently a spring applied to any portion of the system will effect the proper suspension or support of the bed. I further have contrived, however, a mechanism by which such a spring may be conveniently placed and readily and securely adjusted. For this purpose I provide a third arm affixed to or integral with one of the said levers and projecting downward from the pivot thereof, and I pivot to the free extremity of the said arm one end of a rod, whose other end passes through a stationary collar and has confined upon it a spring provided with adjusting members. Thus in the drawings, 30 is the third arm of the lever 18 and projects downward and has pivoted to its extremity at 31 a rod 32. The said rod projects forward and is screw-threaded at its forward end and has mounted thereon the nut 33 and check-nut 34, respectively, provided with the hand-wheels 35 36. The rod 32 passes through and plays in the sleeve 37, which latter is externally screw-threaded and is provided with a hand-wheel 38. The said sleeve in turn passes through the collar 39, but does not play freely in the same, the collar being internally screw-threaded to engage with the external threading of the sleeve. The said collar is held stationary with respect to the frame of the machine by being pivoted at 40. Such pivoting is required to accommodate the collar to the varying angle assumed by the rod with the swing of the arm 30 as the table yields to the pressure which is applied thereto.

42 is a spiral spring encircling the rod 32 and confined between an abutment 43 thereon and an abutment 44 on the rear end of the sleeve 37.

The adjustment of the foregoing mechanism is accomplished as follows: When it is desired to lower the table without disturbing the tension of the spring 42, the hand-wheel 38 will be so turned as to move the sleeve 37 forward in the collar 39. Such movement does not disturb the relative position of the rod 32 and sleeve 37. When, on the other hand, it is desired to adjust the tension of the spring 42, the check-nut 34 will be loosened and nut 33 will be turned forward to slacken the spring or rearward to compress it, the effect of such forward motion being to allow more space between the abutments 43 and 44 and the effect of such rearward motion being to allow less space between said abutments.

As will be clear, when the abutments 43 and 44 are brought closer together the bed 16 will be lowered, and when the distance between them is increased the bed will be raised. The bed is therefore susceptible of very accurate and fine adjustment by means of the hand-wheel 35, while the resistance offered by the bed to the pressure or thrust of the pebbling-

roll may likewise be very accurately and finely adjusted by means of the hand-wheel 35.

I have shown my invention in the accompanying drawings as embodied in a pebbling-jack and have described it as therein shown. I do not, however, desire to limit myself to the application of the invention to a pebbling-jack, as a number of machines which operate in a manner similar to a pebbling-jack and which are employed in the finishing of leather—as, for example, jacks for glassing, rolling, stoning, &c.—are equally adapted to the employment of my invention.

I claim as my invention—

1. In a leather-finishing machine, the combination with a finishing-tool which travels over the surface of the bed, of a bed for supporting the stock while it is being operated upon, levers adjacent the bed and having their contiguous ends adapted to engage with each other, with their remote ends serving to support the bed, and means for yieldingly sustaining the bed under the pressure of the finishing-tool while its parallelism is maintained, substantially as described.

2. In a leather-finishing machine, the combination with a finishing-tool which travels over the surface of the bed, of a bed for supporting the stock while it is being operated upon, levers adjacent the bed and having their contiguous ends adapted to engage with each other, with their remote ends serving to support the bed, and a yielding member connected with the levers to sustain them against the pressure of the finishing-tool upon the bed, substantially as described.

3. In a leather-finishing machine, the combination of a bed for supporting the stock while it is being operated upon, connected sector-levers supporting the bed, a rod engaging one of the said levers, means for adjusting said rod to vary the position of the levers and thereby effect an adjustment of the bed, and a spring on said rod which tends to hold the said bed in its normal position against the pressure of the finishing-tool, and means for adjusting the tension of the said spring, substantially as described.

4. In a leather-finishing machine, the combination with a bed for supporting the stock while it is being operated upon, connected sector-levers for supporting the bed, a rod engaging one of the said levers, a sleeve on said rod, a collar threaded upon the sleeve and pivotally mounted on the frame, means for turning the sleeve within the collar to effect an adjustment of the rod, a spring on the said rod adjacent the said sleeve and an adjusting-nut on the said rod for adjusting the tension of the spring, substantially as described.

In testimony whereof I affix my signature in presence of two witnesses.

EDWARD B. PARKHURST.
